(57) **CLAIM**

The ornamental design for the lighting fixture backplate, as
shown and described.

DESCRIPTION

FIG. 1 is a side elevation view of the lighting fixture
backplate in accordance with my design, illustrating a possible
environment for the backplate;

FIG. 2 is a front elevation view of the lighting fixture
backplate in accordance with my design;

FIG. 3 is a left side elevation view of the lighting fixture
backplate in accordance with my design;

FIG. 4 is a top plan view of the lighting fixture backplate in
accordance with my design; and,

FIG. 5 is a bottom plan view of the lighting fixture backplate
in accordance with my design.

The broken lines showing environmental structure are for
illustrative purposes only and form no part of the claimed
design. The rear elevation view is unornamented and follows
the contours of FIGS. 2 through 5 and is not part of the
claimed design. The right and left views are mirror images.
